UNITED STATES PATENT OFFICE.

JOSEPH M. VAIL, OF BRYAN, OHIO.

RAIL-CLAMP.

No. 900,328.

Specification of Letters Patent.

Patented Oct. 6, 1908.

Application filed April 18, 1908. Serial No. 427,777.

To all whom it may concern:

Be it known that I, JOSEPH M. VAIL, a citizen of the United States, and a resident of Bryan, in the county of Williams and State of Ohio, have invented a certain new and useful Rail-Clamp; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to railway appliances and particularly to means for clamping rails to their ties; and it has for its object the provision of simple and efficient means of this class, which is easily and quickly adjustable to compensate for wear or a looseness of the rail due to strain or weather conditions.

The operation, construction and arrangement of the parts of the invention are fully described in the following specification, and illustrated in the accompanying drawings, in which,—

Figure 1 is a top plan view of the clamp embodying my invention in association with a rail and tie. Fig. 2 is an end view thereof. Fig. 3 is an enlarged bottom view of the invention. Fig. 4 is an end elevation of a metal tie with which the clamp is associated, and Fig. 5 is a bottom view of such tie.

Referring to the drawings, 1 designates a tie and 2 a rail clamped thereto. While the ties 1 may be of any construction suitable for the bolting or securing of a clamp thereto, those of I-beam shape are preferably used due to the facility with which the clamp-bolts may be passed through the flanges thereof. The tie shown in the drawing is of a modified I-beam construction and is provided on its bottom with the longitudinally-extending downwardly-projecting web or flange 3, which is vertically slit near its ends, as shown at 4. The flange 3 is then slit from the tie base a short distance in both directions from the slits 4 to form the wings 5, which are bent in opposite directions laterally of the flange to provide simple and efficient means for anchoring the tie against longitudinal movements.

Referring to the rail clamp forming the features of my invention, 6 designates a plate which is fixedly secured to the tie 1

in contiguous position to one base flange of the rail by a bolt 7 passing through said plate and one of the top flanges of the tie, as shown. The plate 6 has one end formed with the projecting stem 8, which is threaded to receive the nut or nuts 9, and has the lower edge of the side thereof which is disposed toward the rail base recessed or cut-away, as at 10, to form a seat for the wedge key 11. This recess has its rear wall preferably disposed approximately in a plane with the inner or rail side of the stem 8 and rounded to enable the key 11, which has its coating surface similarly fashioned, to turn slightly therein to adjust itself to the degree of taper or incline of the top surface of the rail base-flange.

The key 11 has the end thereof which is contiguous to the stem 8, formed with a lateral boss or projection 12, which is provided with an opening, not shown, through which the stem 8 loosely projects. The lower outer edge of the key is recessed or cutaway, as at 13, to adapt it to partially overlap the base flange of the rail, and this recess has its rear wall tapered or inclined relative to the front or outer edge of the key to form the key with its wedge-shaped base portion 14, which has its broad end disposed at the end of the key from which the boss 12 projects, as best shown in Fig. 3.

In securing a clamp to a tie and in engagement with a rail-base, the plate 6 and key 11 are assembled in proper position with the stem 8 projecting through the opening in the boss 12 of the key and the opposite end of the key terminating substantially at the end of the plate opposed to the stem, and the whole is then placed on the tie with the recessed portion of the key receiving the base-flange of the rail and its rear or tapered wall bearing against the edge of such flange, as shown. The plate 6 is then fixed to the tie by the bolt 7 with its stem 8 and the rear wall of its recess 10 standing slightly inclined outwardly from a parallel with the edge of the rail base, due to the inner straight edge of the key bearing against said recess wall and its tapered edge abutting against the rail base. It is thus apparent that a tightening of the nuts 9 on the stem against the boss 12 of the key will move the key longitudinally relative to the plate 6 and rail and effect a wedge-like action against the opposing surfaces thereof, thus forcing the rail tightly against the opposing clamp 15 on the op-

posite side of the rail, as it may be desired to originally secure the rail to the tie or to compensate for wear or other loosening conditions and maintain uniform track gage. 5 Should the clamps be used on electric railways it is apparent that they may be insulated from the rails and tie in the usual or any suitable manner.

I wish it understood that I do not desire 10 to be restricted to the exact details of construction and arrangement of the parts shown and described, as obvious modifications will be apparent to persons skilled in the art.

15 Having thus described my invention, what I claim as new and desire to secure by Letters Patent, is,—

1. A rail clamp comprising a plate having a key seat in one side thereof and a stem projecting from its end, a wedge key movable in said seat and having a part receiving said stem, means carried by the stem and movable thereon to effect a longitudinal movement of the key and means for fixing the plate to a 25 tie.

2. The combination with a tie and rail, of a member fixed to the tie and having a key-seat in the side contiguous to the rail and a stem projecting from one end thereof, a key 30 mounted for movement in said seat and having a part overlapping the contiguous base flange of the rail and a longitudinally tapered part coacting with the edge of said

flange whereby a movement of the key in one direction effects a wedge-like action between the rail-base and member, and means carried by the stem for moving the key. 35

3. The combination with a tie and rail, of a member fixed to the tie at the side of the rail-base, and having a stem projecting from one end thereof, a wedge key working between the edge of the rail-base and said member, said key having a part which is held in contact with the top of the rail-base flange by said member and a laterally projecting 45 part which receives the stem, and a nut threaded to the stem without said latter part and adapted to turn thereon and force the key between the member and rail-base. 40

4. A metal tie of I-beam construction in 50 cross-section having its base formed with a downwardly projecting flange, said flange being transversely slit at spaced points therein and longitudinally slit a short distance in either direction from each transverse slit to 55 form wings, the contiguous wings being horizontally bent in opposite directions relative to the beam, substantially as described.

In testimony whereof I have hereunto signed my name to this specification in the 60 presence of two subscribing witnesses.

JOSEPH M. VAIL.
